UNITED STATES PATENT OFFICE

EVERETT K. WOLFE, OF NEW YORK, N. Y.

TOY BUILDING UNIT

Application filed January 30, 1930. Serial No. 424,542.

My invention relates to toy building units, more or less analogous to toy building blocks, and suitable for use by children and young persons generally, for the purpose of erecting toy composite structures of different kinds.

More particularly stated my invention contemplates a number of toy building units so formed and arranged that they may be 10 detachably fitted together to form such articles as wagons, animal cages, buildings, aeroplanes and the like, the parts required for this purpose being merely a few pieces of wood or analogous material and a few pieces 15 of cardboard, each of the parts being of relatively simple design.

Reference is made to the accompanying drawings forming a part of this specification, and in which like reference characters indicate like parts throughout all of the figures.

Figure 1 is a perspective, showing a small number of my improved building units disconnected from each other and ready for use.

Figure 2 is a plan view of a toy wagon 23 made up of a few of my improved building units.

Figure 3 is a section on the line 3—3 of Figure 1, looking in the direction indicated by the arrows.

Figure 4 is a perspective of a toy bear cage made up of my improved building units.

Figure 5 is a perspective of a toy chair made up of my improved building units.

Figure 6 is a perspective of a toy building 35 made up of my improved building units.

Figure 7 is a fragmentary section, indicating how the roof shown in Figure 6 is mounted in position.

Figure 8 is a perspective of a toy aeroplane model made up of a few of my improved building units.

A number of small building beams are shown at 9, 10, 11 and 12, and are substantially alike except as to length.

A connecting block is shown at 13 and is of substantially cubical form in general outline.

A connecting disk is shown at 14, and with 55 others of its kind is adapted for cooperation

with the other building units, as occasion may require.

Each building beam 9, 10, 11, 12 is provided adjacent its ends with a pair of socket holes 15, 15, crossing each other. Each 55 building beam 9 and 10 is further provided with another pair of socket holes 16, 16, adjacent its middle portion and likewise crossing each other.

Each of the four building beams 9, 10, 11 60 and 12 is substantially square in cross section and is provided upon each of its four faces with a longitudinal slot 17, extending throughout the entire length of the beam as may be seen from Figure 1.

Each of the four building beams just mentioned is further provided with extending portions 19, 19, formed into dowel pins, which are of proper size to fit rather tightly 70 into the holes 15, 15, 16, 16.

The beam 10 is in addition provided with two pair of socket holes 20, 20, extending entirely through the beam and crossing each other as indicated in Figure 1.

The connecting block 13 is provided with a pair of socket holes 21, 22, extending entirely through it and crossing each other, as indicated in Figure 1, and is further provided with kerf slots 23, upon four of its 80 sides.

The connecting disk 14 is provided with a hole 24 extending centrally through it, and is further provided with additional holes 25 extending radially inward from its 85 periphery.

The frame of the toy wagon shown in Figure 2 is made up by fitting together two beams 9, 9 and two other beams 12, 12, together with a card 26, the edges of which 90 are fitted into the adjacent slots 17 of the building beams 9, 9, 12, 12.

A cord or string 27 is connected with one of the beams 12 and may be used for pulling the wagon.

Four fastenings 28, which may be ordinary paper fasteners, are thrust through the central holes of four connecting disks 14 and through four sets of socket holes 20, 20, and spread or clinched as shown in Fig. 100

ure 2. This holds the four wagon wheels in place.

The holes 25, extending radially inward of the disks 24, are somewhat suggestive of the ends of spokes, and thus improve the appearance of the wagon.

If the wagon be left in this condition, it is more or less analogous to a flat truck, such for instance, as may be used for hauling stone. However, if desired, a top framework can be added, by means of a number of beams 12, 12, as indicated by dotted lines in Figure 3.

In Figure 4 I show an animal cage. A number of building beams 9, 9, 10, 10, 11, 11 are fitted together somewhat after the manner of the frame of a small building, and a number of pieces 29, 29 are fitted into the various kerf slots 17. Spaces 30, 31, are left between the cardboard pieces, and these spaces may be considered as doors, or may be merely used as openings through which the interior of the cage may be readily observed.

25. A card 32 is fitted edgewise into the kerf slot 17 of one of the beams 9, located substantially centrally within the cage, and this card carries a picture 33 of a brown bear, together with the legend Brown bear.

30. Of course any other animal could be substituted for the brown bear.

In Figure 6 I show a small building made up of my improved building units. In constructing the framework I use a number of building beams 11, and also a number of building beams 37, these last mentioned building beams being like the building beams 9 above described, but a little longer.

At one end of the building is a card 36, provided with a picture 37 of a window, and another card 38, having a picture 39 of a door. These two cards 36 and 39 are fitted into the adjacent slots 17 of the building beams.

45. Two other cards 40, 40, provided with pictures 41, 41 of windows, are similarly fitted in position, and constitute the side wall of the building.

50. A roof 34 is made of a single piece of cardboard, bent or creased to form a cornice 36.

This piece of cardboard is also bent along two of its outer edges, and the latter are thrust into the adjacent kerf slots 17, as may be understood from Figure 7. By this arrangement the house shown in Figure 6 is provided with a rather substantial roof, well fitted into position.

Figure 8 is a perspective of a toy aeroplane model.

Carried by a long beam 32 is a connecting disk 14, which in this instance represents the aeroplane propeller.

65. Two cards 42, 42, are stuck edgewise into the oppositely disposed slot 17 of the beam-

32, and simulate the wings of an aeroplane.

The fuselage is made by bending a card as shown at 43, so as to form a trough-like member provided with flat portions 44, 44, extending inwardly and toward each other, 70 the edges of these portions being neatly fitted into the slots 17.

Four cards 45, 45 are thrust edgewise slightly into the four slots 17, and serve the purpose of horizontal and vertical steering 75 rudders.

Of course the number of building units of each particular kind may be increased or diminished as circumstances may require, and the various units may be grouped together 80 to form articles which are simply innumerable.

Of course as many units of each kind may be employed as occasion may require.

I do not limit myself to the precise construction shown, as variations may be made therein without departing from my invention the scope of which is commensurate with my claim.

Having thus described my invention, what I claim as new and desire to secure by Letters Patent is as follows:

A toy building unit intended for use as one of a plurality of similar units adapted to be connected together to form a toy building structure, said unit consisting of a single elongated member of substantially uniform square cross section throughout its length, said member having slots extending longitudinally along the length of each of its four side surfaces of a character to receive wall forming plates therein, said member also having holes formed transversely therethrough in pairs spaced apart along the length of the member, the two holes of each pair crossing each other in the same plane transversely of the member and being arranged so that the two ends of one hole open through two opposite slots of the member while the two ends of the other hole open through the remaining two slots of the member, said holes being all of the same size, and said member also having dowel-like projections formed thereon at its opposite ends extending in the direction of length of the member and each of the same size as said holes adapted to be snugly received in any selected holes of other members.

Signed at New York City, in the county of New York and State of New York, this 29th day of January, 1930.

EVERETT K. WOLFE.
